TABULATING CARD

Leo C. Conradi and Almon M. Fairbrother, Bing-
hamton, N. Y., assignors to International Busi-
ness Machines Corp., New York, N. Y., a cor-
poration of New York

Application May 1, 1935, Serial No. 19,180

1 Claim. (Cl. 91—14)

This invention relates to a method of and means for enhancing the value and prolonging the life of record cards adapted to be used in calculating and similar machines where the cards are fed automatically through the machine and analyzed.

5 In machines which are controlled by perforated record cards, the cards are fed by a card picker which is adapted to advance one card at a time from a stack of cards. The cards pass through a restricted throat in which the opening is slightly greater than the thickness of the card so that only one card at a time may pass through. The cards are fed in this way to sensing devices which read the data on the card and control the operation of the machine.

10 The leading edge of the card which encounters the throat eventually becomes worn or otherwise damaged. Also the rear edge which encounters the card picker or pickers becomes damaged. This reduces the life of the cards. The cards 15 used in these machines are usually made of high grade paper stock but although the surfaces of the stock are tough and reasonably resistant to damage by the pickers and the throat, the intervening portion between the surfaces is rather soft and often permits the surfaces to become separated.

20 One of the objects of the invention is to provide means for impregnating the edges of the cards to toughen them generally so that they will last through a greater number of runs through the machines.

25 Another object is to provide means whereby the impregnating substance may be applied to the edges of the cards.

30 Other objects will be brought out in the following description of the invention.

35 While it is common to treat paper and cloth in various ways to render them fire resistant or to produce insulating material or for water proofing, the substances used for these various purposes have been found to be unsuitable for use in treating the edges of cards adapted to be used in calculating and like machines.

40 Various substances cause the edge of the card to become brittle after it is dry so that the action of the card pickers and the throat will damage the edge of the card.

45 Other substances cause the cards to become 50 gummy or sticky while still other substances in drying cause warping of the cards which is not permissible.

55 Various substances which are soluble in water are not well suited for the purpose described because while the edge of the card may become

more resistant to wear than untreated cards, the cards become warped in drying and cannot be used in machines.

Certain other substances tend to build up the edge of the card thus making it too thick to feed 5 properly through the throat of the machine.

Numerous substances soluble in benzol or alcohol or other spirit solvents were tried and found unsuitable for several reasons. One of the reasons is the fire hazard connected with the use of 10 such materials. Another objection to the use of such solvents is that the base substance with which they are used tends to become brittle when dry.

15 It has been found that certain gum substances such as artificial resin ester, phenol formaldehyde and paracumaron indene produce good results. Also, these gums are soluble in carbon tetrachloride and trichlorethylene. These gums when dissolved in these solvents have been found 20 to dry with desirable results. They also penetrate the fibres of the paper stock without producing swelling of the paper to increase the thickness of the cards and without injuriously affecting the sizing of the paper. These substances are 25 also absorbed into the paper sufficiently rapidly to facilitate their application. They also serve 30 their function without interfering with the color striping of the cards. In other words, it is common to stripe the upper edges of the cards with various colors in order to more readily distinguish 35 cards belonging to various groups. The dyes used for striping are usually spirit solvent dyes. Thus, if the impregnating substance is dissolved in alcohol or benzol, the dyes when later applied, 40 tend to partially dissolve or soften the impregnating substance. Where the solvent is carbon tetrachloride or some similar substance the card readily absorbs the dye without any undesirable 45 results.

These substances have been found not to interfere with the natural moisture content of the paper stock from which the cards are made as is common with certain other substances, so that 50 variations of moisture content of the atmosphere 45 do not affect the cards by causing warping or swelling.

Numerous methods of applying the substance to the cards have been tried and it has been found that a moistened wick pressed against the raw 55 edges of the paper stock will supply the substance to be absorbed into the edge of the paper while the latter is being slit into proper widths and wound on reels. A device for performing the operation is shown in the drawings.

Referring to the drawings:

Fig. 1 is a view of a perforated record card having its upper and lower edges impregnated.

Fig. 2 is a perforated record card in which the upper and lower edges have been impregnated and the upper edge has been color-striped to distinguish it from cards of other groups.

Fig. 3 is a front elevation of a device adapted to apply the impregnating substance to the paper stock from which the cards are produced.

Fig. 4 is a section taken on line 4-4 of Fig. 3.

Fig. 5 is a detail of the wick device for applying the substance to the edges of the paper stock.

Fig. 6 is a sectional detail taken on line 6-6 of Fig. 5.

In the drawings a reel of paper stock 1 is shown mounted on a frame 2. The paper 1a is run over guide rollers 3, 4 and through cooperating cutters 5, 6 which slit the paper from the supply roll 1 into several narrow strips 1b which then pass between rollers 7, 8 where the strips are separated, alternate strips running up and being wound upon reels 9 while the intermediate strips run downwardly and are wound on reels 10.

Adjacent to the opposite edges of the strips 1a after they emerge from the rollers 7, 8, are shown wick devices 11 comprising wicks 12 mounted in tubular members 13 reaching outwardly from common supply tubes 14 which run across the machine and are supplied with the impregnating substance from reservoirs 15.

The device is operated by a driving shaft 16 having a gear 17 meshing with a gear 18 on shaft 18a which carries the reels 9. Gear 17 also meshes with a gear 19 on shaft 20 which carries the feed roller 7 and, through gears 21, connects with shaft 22 carrying roller 8. Intermediate gears 23 associated with gear 19 serve to drive a gear 24 on shaft 25 which carries the reel 10.

As the paper is drawn through the slitters the

edges of the strips 1b are drawn against the edges of the wicks 12 as shown in Figs. 5 and 6 and thus absorb the impregnating material.

The cards 26, 27 are eventually cut from the reels 9, 10, into proper lengths and the printing of the index point position numbers is effected in printing presses, after which the punching of the data perforations in the card is effected in perforating machines. These cards show narrow upper and lower margins 28, 29 which have been treated with the impregnating substance. Card 27 also shows a band 30 of color across its upper edge. This color dye overlaps the impregnated edge 28 without dissolving the substance or softening it in any manner.

Guides 31 are provided to keep the strips 1b in contact with the wicks 12 as the diameter of the reels 9, 10 grow.

While there has been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore, to be limited only as indicated by the scope of the following claim.

What is claimed is:

In a paper treating device, means for slitting a strip of paper, means for separating the edges of the paper thus slit, means for applying an impregnating solution simultaneously to the separated edges, said last named means comprising separate wick devices associated with the said edges and connected to a common supply, and means for winding the slit and impregnated portions of paper on separate reels.

LEO C. CONRADI,
ALMON M. FAIRBROTHER.
